UNITED STATES PATENT OFFICE.

CLARENCE L. RICH, OF SIOUX FALLS, SOUTH DAKOTA.

MECHANICAL FOOTBALL GAME.

Application filed March 27, 1923. Serial No. 628,056.

To all whom it may concern:

Be it known that I, CLARENCE L. RICH, a citizen of the United States, residing at Sioux Falls, in the county of Minnehaha and 5 State of South Dakota, have invented certain new and useful Improvements in Mechanical Football Games, of which the following is a specification.

The present invention relates to a game, in 10 imitation of football.

The invention aims at providing a board to be placed on a table, and upon which a football field is represented, so that a game may be played by two opponents, following 15 practically the same rules as are used in the real football game. The field is accordingly divided into sections, representing ten-yard sections in the football field, and provided with goals and obstacles for the ball 20 approaching the goals.

In the accompanying drawings one embodiment of the invention is illustrated; and

Figure 1 represents a plan view of the game board partly in section;

25 Figure 2 is a transverse section along line 2-2 of Figure 1;

Figure 3 is a side elevation of a tube for guiding the ball; and

30 Figures 4 and 5 are perspective views of different kinds of obstacles or hazards which are placed in the path of the ball.

In the drawing reference numeral 110 represents a board, a suitable size of which is about eighteen inches long by twelve inches 35 wide and of sufficient thickness for keeping the top surface level and smooth. In order to keep a ball from running off the board, a raised edge or fence 11 is placed on three sides thereof. This fence has a height of 40 about one quarter of an inch above the surface of the board.

At the fourth side, as seen in Figure 1, about five inches width of the board is taken up by a stationary chute 12 sloping from the 45 outer or upper edge of the board in the direction of line 13 thereof. At each end of the board and about one inch from the edge thereof are provided border lines 14 and 17, and a longitudinal border line 15 is similarly provided along the bottom edge of the 50 board, as seen in Figure 1. The space between lines 13 and 15 is divided into two fields A and B by a line 16 running in longitudinal direction of the board between the 55 border lines 14 and 17. Transverse lines 18 extend between the lines 13 and 15 and par-

allel to the lines 14 and 17 dividing the space between the two latter lines into ten equal sections, each corresponding to about ten yards width on an actual football field. 60 These spaces are numbered consecutively by tens from left to right, the numbers ranging from ten to one hundred, and upon the chute 12 corresponding lines 19 with similarly numbered fields are shown. 65

The field A has along each of the division lines 18 and near the longitudinal line 13, eleven guides 120, preferably made of wire with bent down ends stuck into the top of the board. The height of these guides above 70 the surface of the board is about one quarter of an inch and the length of each guide about an inch and a half. Between these guides in the middle of each section, is placed a hazard or obstacle 21 in the shape of a V, 75 as seen in Figure 5, having two diverting shanks 22 with hooked ends 23 for securing the obstacle in the board. The apex of this obstacle is placed about midway between the ends of the guides 120 and in exact medial 80 position between two of them with the shanks 22 extending beyond the lower ends of the guides 120, as seen in Figure 1, and the apexes facing the chute 12. Other similar obstacles 24 are shown in the center of each 85 field but nearer the longitudinal line 16 and constructed in the same manner, but approximately twice as long as the first named obstacle 21. These obstacles 24 point in the same direction as the obstacle 21, that is to 90 say, with their apexes toward the chute 12.

Between the large obstacles 24 and the longitudinally positioned lines 16 are placed eleven arcuate stops 26 extending across the division lines 18, with their ends meeting almost on the middle line of each section. That is to say, a small opening 140, which will not permit the ball 25 to pass between the stops 26, is centered between the ends of the shanks of the large obstacles 24. These 95 arcuate stops are also provided with hooked ends 27 for securing them in the top of the board 110.

At each end of the field B is provided a gate or goal 29 placed on the border lines 14 and 17 respectively. The construction of these goals is best shown in Figure 2 and they are made with upright legs 130 for securing them in the top of the board in similar manner as the guides 120 and obstacles 110 21 and 24. The height under the goals is, however, greater than what is the case with

the obstacles and guides so that the ball 25 can pass under them with ease and out beyond the border line 14 or 17. Directly in front of each goal 29 are positioned a number of pegs 31 in the sections 10 and 100, three being shown in the drawings, and other pegs 32 are placed in the next fields 20 and 90 respectively opposite the center of the spaces between the first pegs 31. On the 10 division lines 18 between the sections 30 and 40, 50 and 60, and 70 and 80, and approximately in the center line of the field are positioned single pegs 33, all these pegs forming obstacles for the free passage of the ball 15 along field B to either one of the goals 29.

The chute 12, as already described, slants inwardly from the top edge of the board 110, as seen in Figure 1, and centrally in each 20 section of the chute is furnished a small pocket 35 adapted to receive the ball 25. From each pocket 35, a channel or passage 36 leads down to the top surface of the board into the field A. These passages run parallel to the division lines 19 in the chute, so 25 that the lower end of each passage faces the corresponding apex of the smaller obstacles 21. Between the guides 120 and the longitudinal line 13 is placed an intermediate runway 45, the top face of which is inclined 30 to form a continuation of the channels 36.

Referring particularly to Figure 3, this shows the guide tube or what might be called a "kick-off" tube 37, which has a pair of legs 39 for supporting the tube on the board, the 35 lower end resting on the top thereof. The upper end of the tube is adapted to receive a ball 25 and the main inclination of the tube is approximately 25° gradually changing into horizontal at the lower end of the 40 tube. This "kick-off" tube is in this manner loosely supported on the board, so as to be placed wherever the player selects in accordance with the rules of the game, but this 45 guide tube is not intended to be used elsewhere, but on the field B.

The chute 12 has also an inclination of its 50 passages of about 25° against the top surface of the board, but differs from the guide tube 37 by being stationary thereon. A ball placed in one of the pockets 35 will thus roll 55 down the channel or passage 36 in the chute and strike the apex of the small obstacle 21, so as to be diverted from its straight course either to the right or the left of the obstacle 55 the aim of the player being to have the ball pass from the section into which it is played, into the next section ahead or towards the goal at the opposite end of the field from which his play starts.

60 The rules of the game may be as follows. The game is intended to be played by two opponents, one starting from each end of the board, so that the player at the end of the board where the number 10 section is 65 situated, aims at reaching the goal 29 placed

at the end of the section marked 100, and his opponent plays in the opposite direction, aiming to reach the goal 29 at the end of section 10.

The game is started by placing the guide or "kick-off" tube 37 on the line between sections 50 and 60. Wherever the ball stops or passes out of bounds the play is ended for the starter and his opponent takes the ball. He may then play either through the chutes 75 or he can also use the guide tube 37 as he selects, but the ball must be played from the section where it stopped. If he plays from the chute he has the privilege of dropping the ball four times into the pocket 35 of the section in question, but if using the tube 37 for "punting" he can only drop the ball once. Failure of the player to make the next section in four tries reverts the ball to the opponent to be played by him from the same position. When the ball is "punted," the opponent plays the ball from whatever position it has stopped or gone out of bounds. If it has punted past the goal line, 80 the opponent takes the ball to the hole 35 of the 20-yard section with ten yards to go. After making a "touchdown" through the chutes, the winner has the privilege of "scrimmage" from the 20-yard line. 85

The following points may be gained during the play:

For "touchdown," 6 points,

For "goal," 3 points,

For "kick-off" from "touchdown," 1 point.

It is evident that other rules and different 100 points for marking may be used in the course of the play.

Having thus described the invention what is claimed as new is:

1. A game board having a field subdivided by lines into sections, a stationary chute having a passage for each of said sections and in straight alignment therewith, and means for deflecting a ball falling into one of said sections from said chute into another of the sections over said lines. 105

2. A game board having a level field subdivided by lines into sections, a stationary chute having a passage for each of said sections and in straight alignment therewith, 115 said passages having an inclination against the surface of the field and being adapted to receive a ball to pass the same into a corresponding section of the field, and means for deflecting said ball from said section to adjacent sections over said lines. 120

3. A game board having a substantially level field subdivided by parallel lines into sections, a stationary chute along one side of said field having a passage for each of said sections and in straight alignment therewith, said passages having an inclination against the surface of the field and being adapted to receive a ball to pass the same into a corresponding section, and 125 130

means for deflecting said ball from said section to adjacent sections over said lines, the other sides of said field being enclosed by border lines.

5 4. A game board having a substantially rectangular field sub-divided by parallel lines into sections of uniform width, a stationary chute along one side of said field having a passage for each of said sections and in straight alinement therewith, said 10 passages having an inclination of substantially 25° against the surface of the field and being adapted to receive a ball to pass the same into a corresponding section, the 15 other sides of said field being surrounded by border lines, said field having guide members along said parallel division lines between the sections, and wedge-shaped obstacles situated medially between said 20 guide members and pointing in the direction of said chute passages.

5. A game board having a substantially rectangular field sub-divided by parallel lines into sections of uniform width, a stationary chute along one side of said field having a passage for each of said sections and in straight alinement therewith, said 25 passages having an inclination of substantially 25° against the surface of the field and being adapted to receive a ball to pass the same into a corresponding section, the other sides of said field being surrounded by border lines, said field having guide members along said parallel division lines between 30 the sections, and obstacles including wire elements bent in wedge-shape placed medially between said guide members in each section and pointing toward said chute 35 passages.

6. A game board having a substantially rectangular field sub-divided by parallel lines into sections of uniform width, a stationary chute along one side of said field having a passage for each of said sections and in straight alinement therewith, said 45 passages having an inclination of substantially 25° against the surface of the field and being adapted to receive a ball to pass the same into a corresponding section, the other sides of said field being surrounded by border lines, said field having guide members along said parallel division lines between 50 the sections, obstacles including wire elements bent in wedge-shape placed medially 55 between said guide members in each section and pointing toward said chute passages, and a series of arcuately shaped stops placed across said parallel division lines, the ends of said stops substantially meeting 60 medially in said sections.

7. A game board having a substantially rectangular field sub-divided by parallel lines into sections of uniform width, a stationary chute along one side of said field having a passage for each of said sections 65

and in straight alinement therewith, said 70 passages having an inclination of substantially 25° against the surface of the field and being adapted to receive a ball to pass the same into a corresponding section, the other sides of said field being surrounded by border lines, a goal element placed in each of the outermost sections of 75 said field, and pegs placed in staggered relation in some of said sections between said goal elements.

8. A game board having a substantially rectangular field sub-divided by parallel lines into section of uniform width, a stationary chute along one side of said field 80 having a passage for each of said sections and in straight alinement therewith, said 85 passages having an inclination of substantially 25° against the surface of the field and being adapted to receive a ball to pass 90 the same into a corresponding section, the other sides of said field being surrounded by border lines, a goal element placed in each of the outermost sections of said field, pegs placed in staggered relation in some 95 of said sections between said goal elements, and a guide tube erected upon said field so as to be selectively positioned in any of said sections for directing a ball passing through the tube toward one of said goals, said guide tube having an inclination of substantially 25° against the surface of the field.

9. A game board divided into a first and a second field subdivided into an equal number of sections, each section on the first field registering with a corresponding section on the second field, a stationary chute having corresponding passages, each passage registering with a particular section of the first field, said passages having an inclination of substantially 25° against the top surface of the board and being adapted to receive a ball and to pass the same into a section of the first field, said fields being surrounded by border lines; the second field having a goal element placed in each of its outermost sections, guide pegs placed in staggered relation in some of said sections between said 100 goal elements, a guide tube detachably mounted on said second field so as to be selectively positioned thereon for directing the ball passing through the tube, said guide tube having an inclination with regard to the surface of the board of substantially 105 25° ; the first field having guide members between each section and obstacles placed medially on each section, said obstacles comprising wire elements bent in V-shape with the apex facing the corresponding passages, and a series of arcuately-shaped stops placed across the division lines between said sections and terminating substantially in alinement with the apex of the corresponding 110 obstacle. 115 120 125 130

10. A game board divided into a first and a second field subdivided into an equal number of sections, each section on the first field registering with a corresponding section on the second field, a stationary chute having corresponding passages, each passage registering with a particular section of the first field, said passages having an inclination of substantially 25° against the top surface of the board and being adapted to receive a ball and to pass the same into a section of the first field, said fields being surrounded by border lines; the second field having a goal in each of its outermost sections, guide pegs placed in staggered relation in some of said sections between said goal elements, a guide tube detachably mounted on said second field so as to be selectively positioned thereon for directing the ball passing through the tube, said guide tube having an inclination with regard to the surface of the board of substantially 25° ; the first field having guide members between each section and obstacles placed medially on each section, said obstacles comprising wire elements bent in V-shape with the apex facing the corresponding passage, and a series of arcuately-shaped stops placed across the division lines between said sections and terminating

substantially in alinement with the apex of the corresponding obstacle, the sections of said fields being consecutively numbered.

11. A game board having a field divided into sections of substantially the same area, a stationary chute having passages, one for each section, said passages having a suitable inclination for passing a ball placed therein to its particular section, a border space being provided around said field, guide members between each section and in longitudinal direction thereof, and V-shaped obstacles placed medially on each section with the apex facing the respective passage.

12. A game board having a field divided into sections of substantially the same area, a stationary chute having passages, one for each section, said passages having a suitable inclination for passing a ball placed therein to its particular section, a border space being provided around said field, guide members between each section and in longitudinal direction thereof, obstacles placed medially on each section, said obstacles being of V-shape with the apex facing its corresponding passage, and arcuately-shaped stops across the division lines between said sections.

In testimony whereof I affix my signature.
CLARENCE L. RICH. [I. S.]
